UNITED STATES PATENT OFFICE

ARTHUR L. DUNCAN, OF PIEDMONT, CALIFORNIA, ASSIGNOR, BY MESNE ASSIGNMENTS, TO PACIFIC MACHINERY COMPANY, OF SAN FRANCISCO, CALIFORNIA, A CORPORATION OF CALIFORNIA

PITTING AND CORING MACHINE

Application filed May 8, 1928. Serial No. 276,154.

The present invention relates to improved pitting and coring apparatus and comprises improvements over the mechanisms disclosed in my co-pending application, Serial No. 5 191,334, filed May 14, 1927, and of which the present application is a continuation in part.

It has been observed from actual operation of the machine disclosed in said co-pending application that certain improvements were 10 desirable particularly to insure alignment of parts, to reduce friction, and to simplify and increase the ruggedness, reliability and durability of the mechanisms in operation.

It is accordingly one of the objects of the 15 present invention to provide improved pitting mechanisms in which parts are effectively guided and the various operating members effectively retained in position.

Another object of my present invention is 20 to improve the driving and registering mechanisms to secure more accurate positioning and alignment of the parts; and to minimize friction.

A further object of the present invention 25 is the provision of improved means for preventing sticking or stopping of the mechanism should fruit stems or other matter accumulate between the shank of the pitting knives and the knife holders while the knife 30 holders are in an open position.

A still further object of the present invention is the improvement of mechanism to facilitate the taking apart and cleansing of different parts thereof.

Still another object of the invention is the provision of novel adjusting devices to permit rapid and convenient adjustment of pitting mechanisms for operation on different sizes of fruits.

Further objects of the invention are such as may be attained by a utilization of the various combinations, subcombinations, and principles, hereinafter set forth and as defined by the terms of the appended claims. For a 45 full understanding of the invention reference will be had to the accompanying drawings in which—

Figure 1 is a vertical longitudinal sectional view through a preferred improved pitting 50 or coring machine embodying my invention.

Figure 2 is a longitudinal sectional view through my improved jaw holder adjusting means.

Figure 3 is a part sectional view and part 55 elevational view disclosing particularly the pivoted guiding means for the sections of the oval box cam utilized in my invention.

Figure 4 is a transverse sectional view taken on line 4—4 of Figure 1, particularly disclosing my improved means for setting the 60 main drive shaft into rotation and the means for arresting such rotation.

Figure 5 is a more or less diagrammatic view showing the relation of the side guide 65 bars to the opposing knife holders in the preferred form of invention.

Figure 6 is a top plan view of the head end 70 of the drive shaft utilized in the form of invention disclosed with the gauge plates therein, and

Figure 7 is a sectional view taken on line 7—7 of Figure 6.

Referring to the accompanying drawings by reference characters in which like characters designate like parts, 1 designates a base 75 casting, to which bearing bracket 2 is secured by cap screws 3. Secured to casting 1 is casing section 4 in which worm 5 is disposed. Worm 5 is rigidly secured to and driven by drive shaft 6 which is supported 80 in a suitable bearing as shown in said co-pending application of supporting bracket 7 secured to base 1 by cap screws 8. Power is transmitted to drive shaft 6 from a suitable pulley as shown in said co-pending application. Meshing with and driven by worm gear 5 is an assembly consisting of a worm ring gear 9 secured to a hardened sleeve 11 provided with a bushing 12. This assembly 85 is journaled for rotation on sleeve 13 constituting a part of the main cam of the machine to be later described. Formed in a face of sleeve 11 is a series of spaced clutch holes 14 adapted to receive a projection 15 of sliding clutch member 16 for a purpose later 90 described. Clutch member 16 is mounted in a suitable bore formed in clutch disk 17 which in turn is keyed to and drives sleeve 13. Clutch member 16 is normally yieldingly urged towards sleeve 11 by means disclosed 95

100

in said co-pending application, and further means as disclosed in said co-pending application are provided for normally holding projection 15 from engagement with holes 14.

6 Sleeve 13 is journaled for rotation on hollow main shaft 18 and mounted on shaft 18 contiguous to clutch disk 17 is a unitary assembly comprising a sleeve 19, ratchet disk 21, and registering disk 22, sleeve 19 being secured to shaft 18 by a key 23 coextensive therewith. Ratchet disk 21 is provided with diametrically opposite ratchet teeth 24 (Figure 4) which are adapted to be engaged by the end 25 of a pawl 26 which is pivotally supported on a pin 27. Spring 28 coiled about pins 29 and 31 engages pawl 26 forcing it about its pivot so that it is normally yieldingly held against the periphery of ratchet 21. Pins 27, 29 and 31 are rigidly secured to clutch disk 17 and accordingly pawl 26 which is pivotally supported on pin 27 is carried by clutch disk 17. Pawl 26 is provided with an extension 32 which is adapted to engage the upper end of throw-out latch 33 which is secured on an extension of rear bearing bracket 34 by means of securing studs 35. Oppositely positioned adjusting stop screws 36 threaded in extensions 37 of bearing bracket 34 are provided for adjusting latch 33 to vary the point in the cycle of operation at which extension 32 of pawl 26 will engage the end of latch 33.

35 Bearing bracket 34 is suitably secured to base casting 1 and is provided at the upper end thereof with a rear bearing 38 which in turn is provided with a bushing 39 in which sleeve 19 is rotatable. Secured to rear bearing 38 by suitable securing devices 41 is a 40 plate 42 to which is pivotally secured by means of pin 43 the inner end of a registering finger 44 provided with a shouldered projection 45 adapted to enter one of a pair of diametrically opposed shouldered notches 46 in the periphery of registering disk 22. Plate 42 is provided with a projection 47 in which is secured an adjusting screw 48 provided with a socket 49 for receiving one end of a helical spring 51 whose opposite end rests in a 50 socket 52 in registering finger 44 in a manner normally urging finger 44 towards and in engagement with the periphery of registering disk 22. Extending through a projection of plate 42 is a shock absorbing adjusting screw 50.

55 Secured to clutch disk 17 is a kick-out pin 53 (Figure 4) adapted upon rotation of disk 17 to engage an edge of registering finger 44 to throw projection 45 out of engagement with a notch 46 just prior to engagement of end 25 of pawl 26 with one of the ratchet teeth 24.

60 Main shaft 18 has formed integrally with the inner end thereof a head 54 slotted or bifurcated to form a central guide slot 55

which inwardly of the end of head 54 is widened providing a substantially square slot 56. A pair of slidable gauge plates 57 (Figures 1, and 5 to 7) are disposed in slid-
70 able engagement with the guide slot 55, the plates being secured by suitable rivets or screws 58 to a member 59 having a cylindrical body 61 that is slidably mounted in an enlarged bore 62 of hollow main shaft 18. Body 61 has a forward projection 63 to which plates 57 are secured. Member 59 is bored axially as shown at 64 for a purpose present-
75 ly to be described and has secured thereto a tubular operating rod 65, the bore of which registers with the bore 64 of member 59. Slidably supported in bifurcation 55 of head 54 and guided for reciprocation between gauge plates 57 are knife holders 66, each of which at the outer end thereof is pro-
80 vided with a bore 67 (Figures 1 and 5) which in cross-section is elongated or of elliptical formation and mounted in each bore 67 is a roller supporting pin 68 which is held in bore 67 by a pin 69 extending through knife holder 66 and transversely of pin 68 at the rear end thereof. By mounting pins 68 in elliptical shaped bores and pinning them at one end the pins are prevented from longitudinal displace-
85 ment in the bores but are permitted a limited rocking movement in bores 67 about pins 69. Each pin 68 extends outwardly from its res-
90 pective knife holder 66 and has rotatably supported thereon a roller 71. Rollers 71 are engaged in a groove or guide 72 of a two-part 100 oval-shape box cam member 73 (Figure 3) comprising an upper member 74 and a lower member 75 which are duplicates and when put together provide an endless oval shaped cam guide groove through which rollers 71 move and thus determine the path of bodily move-
105 ment of the knife holders 66. Each cam member 74 or 75 is provided with a pair of spaced apertured ears 76 between which an apertured ear 77 of a sliding jaw holder 78 is disposed and pivotally secured thereto by a pin 79. Jaw holders 78 are thus pivotally se-
110 cured to cam members 74 and 75 and are re-
cessed to receive a pair of opposing jaws 81 (Figure 1). Jaws 81, as fully disclosed in
115 said co-pending application, are of a single width to enter an annular groove or channel formed in the fruit to be pitted. Jaw holders 78 except for the pivoted ears 79 above referred to are substantially formed as those disclosed in said co-pending application, the outer surfaces being finished and arranged to slide in castings 82 and 83 secured to base 1 of the machine.

120 Each of the cam members 74 and 75 is pro-
125 vided on opposite sides thereof with channel shaped guides 84 (Figure 3) for receiving guide bars 85 which at their lower ends are pivotally secured at 86 to lug members 87 extending outwardly from casting 82 and 130

which at their upper ends are detachably secured to brackets 88 extending outwardly from casting 83, each detachable connection comprising a pin 89 extending outwardly from bracket 88 and provided with a notch 91.

Each bar 85 is provided with an aperture to seat pin 89 and provided with a suitable latch member 92 spring pressed into engagement with notch 91 and a knob 93 for retracting latch 92 from engagement with notch 91. By this construction it will be seen that when it is desired to remove cam 72 for cleaning purposes or to substitute cams with paths of different shape this may be rapidly accomplished by freeing the upper ends of guides 85 and swinging them downward to clear the way for the removal of the cam members 74 and 75. With the guides swung downward the cam members may be readily removed and replaced, and when the cam members are replaced guides 85 may be latched back in the position shown.

Jaw holders 78 are bored in vertical alignment as indicated at 94 (Figure 1) to slidably receive sleeves 95, each of which is provided with a shoulder 96 providing a stop to limit the movement of sleeve 95 in one direction. Sleeve 95 is externally threaded to receive a nut 96 and a coil spring 97 surrounding each sleeve and abuts against nut 96 and a shoulder formed by a recess in jaw holder 78 as shown at 98. It will be apparent that the tension of spring 97 may be adjusted by manipulation of nut 96.

Each sleeve 95 is bored axially as shown at 99 for slidably receiving rod 101, the inner end of which is threadedly engaged in a block 102 from the opposite sides of which extend a pair of pins 103 to which are pivotally secured the outer ends of a pair of links 104 whose inner ends receive therebetween and have secured thereto by pin 105, one end of a lever 106. The outer ends of rods 101 project outwardly of nuts 96 into bifurcations 107 (Figures 1 and 2) of members 108 whose inner ends are threadedly engaged with the outer ends of sleeve 95 and bear against nuts 96. Secured to and extending transversely of bifurcations 107 are pins 109 which extend through heads 111 of rods 101, which heads are provided with eccentric apertures 112 in which are disposed eccentrics 113 of levers 114 which are pivotally supported by pins 109. Members 108 at one side thereof are provided with bores 115 extending from the outer faces thereof to the bifurcations 107. The outer ends of bores 115 are threaded as at 116 for detachably receiving a threaded plug 117 (Figure 2) which engages one end of coil springs 118, the opposite ends of springs 118 nesting in cup shaped members 119 which present a substantially semispherical surface 121 adapted to engage a series of locating notches in levers 114. By this construction the levers 114 are

frictionally held in adjusted position, but may be readily shifted to different positions to adjust the outward travel limit and relative positions of the jaws for different sizes of fruits.

Jaw holders 78 are caused to reciprocate towards and from each other by levers 106 pivoted to frame castings 82 and 83 by pins 122 intermediate their ends, and which as before stated are pivotally connected to rods 101 at their forward ends, the other ends being connected by means of links 123 to the long arms 124 of a pair of bell crank levers 125. The short arms 126 of bell crank levers 125 are connected together by link 127 of the construction specifically disclosed in said co-pending application to the opposite ends of which arms 126 are pivotally secured by means of pins 128. Link 127 is provided with an outwardly projecting stud 129 on which is mounted the cam roller 131 which rides in a cam groove 132 in main cam 133 of the construction disclosed in said co-pending application and which is provided with the sleeve like extension 13, above referred to, and an oppositely extending sleeve like extension 134.

Main shaft 18 is successively reduced from head 54 thereof towards the threaded extremity thereof providing shoulders 135 and 136. The sleeve like extension 134 bears against shoulder 135 and sleeve 19 bears against shoulder 136 in proximity to end of sleeve 13. Sleeve 19 extends through bushing 39 and terminates substantially flush with the outer face of rear bearing 38 and a nut 137 engages the threaded extremity 138 of shaft 18 which forces the sleeves 19 and 134 into substantial contact with the respective shoulders 136 and 135.

Knife holders 66 each have rigidly secured to one face thereof by means of rivets 139 (Figure 5) a side guide bar 141. The guide bar of each knife holder is adapted to slidably engage the opposite knife holder upon inward and outward movement of the knife holders, the engaging faces of knife holders 66 and guide bars 141 being finished to present smooth engaging surfaces. Guide bars 141 slidably move in the enlarged portion 56 of head 54 and slots 142 are provided in bars 141 through which gauge plates 57 may extend. Formed in knife holders 66 are suitable rectangular recesses adapted to receive rectangular shanks 143 of the curved pitting knives 144 shaped to conform to the contour of the core desired to be removed and provided with beveled cutting edges. Shanks 143 of knives 144 are removably retained in the rectangular recesses by set screws 145. Each knife holder 66 is bored from the inner edge thereof to the bore 67 in which pin 68 is positioned, the inner ends of bores being tapped to receive removable threaded plugs 146 (Figure 1) between which

115

120

125

130

and pins 68 coil springs 147 are positioned in said bores by means of which a yielding connection is provided between knife holders 66 and cam 73. The pivotal support of pins 68, and the action of springs 147 permits operation of the knives and holders without injurious wedging due to accumulation of matter between the shanks of the knives and holders in operation. One of the jaw holders 78 is provided with an adjustable limiting screw 148 to limit the movement of the jaws 81 toward each other.

Operating rod 65 for gauge plates 57 passes axially through the hollow shaft 18 and is provided with an internally threaded guiding sleeve 149 adjustably threaded thereon by means of which the position of gauge plates 57 when in operation may be readily adjusted in accordance with the size and varieties of fruit being handled. Sleeve 149 has a guiding extension 151 slidably mounted in an enlarged bore 152 of shaft 18 and is provided with a groove 153 to receive a fork of an operating member 154 which is provided with a bore 155 that receives the end of an operating rod 156. Rod 156 is secured in head 157 of a slidable member 158 having a sleeve member 159 at right angles to head 157 and slidably mounted in a bushing 161 secured in bearing 162 of bearing bracket 34. Extending into sleeve 159 and having one end thereof threadedly secured to member 158 is a rod 163 whose opposite end is provided with a bifurcated head 164 which is pivotally secured to long arm 124 of lower bell crank lever 125 by means of pin 165.

Means are provided for clearing the machine of pits or cores which comprises a pit kick-out rod 166 extending through a longitudinal bore in rod 65 to the outer end of which is pivotally secured by pin 167 one end of link 168 the opposite end of which is pivoted to one end of a link 169. The other end of link 169 in turn is pivoted to a lug 171 projecting outwardly from bearing bracket 34. Pivotally secured to an intermediate portion of link 169 by means of pin 172 is one end of rod 173 which extends into a bore 174 of an elongated boss 175 integral with bearing bracket 34, and has secured to the opposite end thereof a plunger 176 having a rounded end 177 which is yieldingly held in engagement with cam 178 secured to clutch disk 17 by means of a coil spring 179 disposed in bore 174 with one end in engagement with plunger 176 the opposite end being in engagement with a plug 181 threaded into the end of boss 175. Fluid means for removing fruit halves and particles of pulp as disclosed in said co-pending application or co-pending application S. N. 228,352 may if desired be employed in the machine forming the subject matter of this application.

The fruit to be cored is brought into en-

gagement with the jaws and pitting knives in the manner set forth in said co-pending application and which comprises guiding the fruit in position between the jaws and pitting knives by means that form a circumferential recess in a peach in the plane of the suture of the pit in which the pitting knives and jaws are received and which means comprises an upper bracket 182 supported from casting 83 and a lower bracket 183 secured to base casting 1 by cap screws 184. For pitting high grade fruit the upper structure is preferably composed of two blades 185 separated slightly from each other but secured together to move as a unit. Blades 185 are provided with cutting edges 186 and 187 preferably at right angles to each other, the edges of which are inclined outwardly away from the space between the blades, causing the pulp of the fruit to be slightly wedged apart as the circumferential groove is formed. Blades 185 are mounted to swing vertically on parallel links 188 and 189 pivotally secured at opposite ends thereof to bracket 182 and blades 185 respectively. Yieldable adjustment means 191 as disclosed in said co-pending application are provided for limiting the position of links 188 and 189, and consequently of blades 185 for varying sized pits. The lower blade structure preferably comprises two spaced blades 192 adapted for swinging on a horizontal line by means of parallel links 193 and 194 pivoted at their opposite ends to bracket 183 and blades 192 respectively. A coil spring 195 suitably maintains the lower blade structure in position.

Gouges 196 and 197 are arranged between the blades 185 and 192 to transversely cut and remove the narrow strip of the peach that enters between the blades of each set. A tip remover 198 is provided adjacent the path of the peach between blades 185 and 192 for trimming off the tips of peaches as they are fed between blades 185 and 192.

Operation

In operation on peaches, the pitting knives 144 and jaws 81 are normally open lying within the planes of the sides of jaws 81 and gauges 57 are in forward position. A peach to be pitted is inserted in the channel between the blades 185 and 192 with the tip towards the operator and with the plane of the suture of the pit of the peach indicated by a crease on the outside of the fruit, substantially in the vertical plane of the blade. The operator then forces the peach downwardly between the blades removing the tip and cutting channels in the peach in the plane of the suture of the pit. The operator moves the peach to the end of the vertical branch of the path between blades 185 and 192 and then moves it bodily in a horizontal direction between the blades until the stem end of the pit

engages the ends of gauge plates 57. At this point in the operation a circumferential channel recess or groove has been formed around the peach in the plane of the suture of the pit, the pulp halves adhering to the pit are slightly wedged apart, and the peach is in the position for the cutting out of the pit with the suture of the pit between open knives 144 and the inner recessed edges of jaws 81 in which knives 144 are nested, in the channel in the fruit pulp.

Worm ring gear 9 is constantly driven through worm 5 and when a peach has been positioned as above described, the operator 15 manipulates the clutch control lever as disclosed in said co-pending application to cause the projection 15 to enter one of the holes 14 in sleeve 11 thereby imparting rotation to drive clutch disk 17 and consequently to 20 sleeve 13 to which drive clutch disk 17 is secured. Rotation will not be imparted to main drive shaft 18 until kick out pin 53 actuates registering finger 44 and end 25 of pawl 26 carried by the disk 17 engages one of the 25 ratchet teeth 24. During the period between the setting into rotation of drive clutch disk 17 and drive ratchet 21, main cam 133 will be rotated through sleeve 13 shifting connecting link 127 and the bell crank levers 125 and the parts connected thereto to the 30 position of parts shown in Figure 1. As the toggles formed by long arms 124 of the bell crank levers 125 and links 123 straighten jaw holders 78 are brought together and due 35 to the action of the springs 97 yieldingly close jaws 81 and knives 144 firmly about the suture of the pit which has been properly located by gauge plates 57. During movement of jaws 81 and knives 144 inwardly rod 163 connected to long arm 124 of lower bell crank lever through head 157, rod 156, fork 154, connection 149 and rod 65 causes the withdrawal of gauges 57 so that when the pitting knives are rotated the end of gauges 57 will 40 not mutilate the edges of the fruit halves. In this way the jaws and knives automatically adjust themselves to accommodate varying diameters of pits and at the same time center the fruit pit within the compass of knives 144.

50 After the completion of the above operation, kick out pin 53 carried by drive clutch disk 17 engages an edge of registering finger 44 forcing projection 45 out of recess 46 and immediately thereafter end 25 of pawl 26 engages a ratchet tooth 24 of ratchet 21 imparting rotation to ratchet 21 which with registering disk 22 and sleeve 19 are keyed to drive shaft 18 and thereby driving main shaft 18. The rotation of shaft 18 causes rotation 55 of knife holders 66 and knives 144 through half of a revolution. Rollers 71 moving in cam grooves 72 determine the shape of the central core including the whole pit to be cut from the fruit. Grooves 72 defining a 60 substantially oval path cause knives 144 to

follow a path corresponding approximately to the shape of the pit sides to eliminate the waste of desirable pulp portions that occurs when the knives follow a true circular path in pitting fruit with pits not circular in transverse section.

70 After the completion of a half revolution of shaft 18, extension 32 of pawl 26 engages the end of throw-out latch 33 throwing end 25 of pawl 26 out of engagement with ratchet tooth 24, thus serving to disconnect clutch disk 17 from ratchet 21. At the same time projection 45 of registering finger 44 engages a notch 46 on registering disk 22, serving to 75 positively center and hold shaft 18 in proper position for the next operation with knives 144 again nested in the recesses of jaws 81. Continued rotation of sleeve 13 actuates cam 133 to break the toggle consisting of arms 123 and 124 to separate the knife holders 78 together with jaws 81 and knives 144. As the 80 parts separate cam 178 secured to drive clutch 17 engages the rounded end of plunger 176 which through rod 173, links 168 and 169, imparts a reciprocating motion to the pit kick out rod 166 which ejects the pit from between the knives 144 and the fruit pulp halves.

85 For each complete pitting operation, drive clutch disk 17 makes one complete revolution at the end of which projection 15 of pin 16 is 90 withdrawn from engagement with aperture 14 by the means disclosed in said co-pending application, at which time the parts will come to rest with knives 144 nested in recesses of jaws 81 and the parts open to receive the next 95 fruit to be cored. If during the operation when knife holders 66 are in their open position fruit stems or other particles should accumulate between the shanks of knives 144 and holders 66, the pivotal mountings of pins 68 and the action of springs 147 mounted in bores in holders 66 permits a yieldable 100 action between the cam members 74 and 75 of oval box cam member 73 and holders 66 whereby the action of knives 144 is cushioned, 105 thus avoiding danger of stopping of the machine as well as injury to parts.

110 It will be seen that shoulder 45 of latch 44 cooperating with notches 46 of the disk 22 positively locates the parts with the pitting knives 144 nested in the recesses of jaws 81 and between the planes of the side surfaces of the jaws 81 in proper position to enter the kerf formed in the fruit by the cutting and guiding knives 185 and 192, and that the shoulder 45 is positively disengaged from the notch 46 before the knife holders are rotated to drive the pitting knives 144 through the flesh of the fruit. This positive aligning action and the related drive structures are important features of the present invention.

115 In operation of the device it may become desirable either to clean the split cam member 73 or to substitute therefor a cam con-

struction of more or less oval shape to handle fruit having fatter or more rounded pits as the case may be. The construction disclosed permits rapid removal of the cam structure by simply depressing knobs 93 (Figure 3) releasing the upper ends of guides 85 from the pins 89, throwing the guides downward about pins 86, and then removing pins 79 to effect disconnection of the cam members from the jaw holders 78. When the cam members are to be replaced they are inserted in the position shown in Figure 3, pins 79 are replaced, and the guide members 85 are swung upward into the side guide channels of the cam members and are latched into position.

To adjust the relative position of jaws 81 and knives 144 and their holders 66 for handling different sizes of fruits, it is simply necessary to swing the levers 114 in the proper direction, rotating eccentrics 113 which will be held in anyone of a plurality of positions by the frictional engagement of latches 121 with the corresponding notches in the side surface of the eccentrics and screw 148 is adjusted correspondingly. By these adjustments the relative position of the jaw holders 78, jaws 81 and the knives 144 carried thereby is conveniently and rapidly changed, without, however, varying the compression of the springs 97 which are adjusted by nuts 96. Accordingly it will be seen that the relative operating positions of the jaws, knives, and knife holders may be rapidly varied to accommodate different sizes of fruit pits without varying the compression of the springs 97 which predetermine the maximum pressure with which the knives, jaws, and jaw holders are forced together by the toggle actions.

The arrangement of split cam 73 guides the pitting knife holders and pitting knives 144 in their course through the fruit, the cam parts being guided in their movement independently of the guiding arrangement of the knife holders 66 by plates 141 in the head of shaft 54. The guide arrangements together with the pivotal yielding connection between the cam member 73 and knife holders 66 overcomes the wedging effect which otherwise would take place at the horizontal position of knives 144 and knife holders 66 when in contact with the narrow part of the oval cam path, in event stems or other foreign matter become embedded between the shanks of the pitting knives and holders while they are in perpendicular position.

Further improvements effected by the present invention will be apparent to those skilled in the art from the foregoing disclosure and it will be apparent therefrom that an improved fruit pitting or coring machine is provided in which the various operating parts have been simplified in construction and the mechanisms improved in general

whereby friction between the different operating parts is reduced, and providing a machine well adapted for the purpose for which it is intended. While the invention has been described somewhat in detail it should be understood that it is not limited to such details and may be modified without departing from the spirit of the invention and that the scope thereof is to be determined from the following claims.

Having described preferred embodiments only of the invention, what is desired to be secured by Letters Patent and claimed as new is:—

1. In a fruit pitting machine; means for separating the flesh of a fruit to be pitted substantially to the depth of a core to be removed; pitting means adapted to enter between the separated flesh; means for rotating said pitting means; and yieldable means for guiding said pitting means in a predetermined path through the flesh of the fruit to be pitted. 80

2. In combination, means for forming a kerf in the flesh of the fruit to be pitted substantially to the depth of a central core to be removed; pitting means; means for positively holding said pitting means in alignment with the kerf formed by said kerf forming means in the fruit to be pitted; means for first disengaging said holding means and thereafter rotating said pitting means through the flesh of the fruit to cut a core therefrom; and means for causing said holding means to positively hold said pitting means in aligned position to enter the kerf of a succeeding fruit to be pitted at the end of a coring operation. 90

3. In combination a pair of curved knives; means for rotating said knives; a cam member having separable parts guiding said knives in their rotation; stationary removable guide members; means for reciprocating said cam parts on said guide members, and pivotal connections between said cam parts and said reciprocating means. 105

4. The combination as set forth in claim 3, in which said guide members are secured in position with a quick detachable connection.

5. A fruit coring machine comprising a rotatable shaft; coring means driven by said shaft; members yieldably connected to said shaft for slidable movement upon rotation thereof; fruit holding means carried by said slidable members; and movable guides pivotally connected to said members for guiding said fruit coring means in the coring operation. 115

6. A fruit coring machine, comprising a rotatable shaft provided with an enlarged head; said head provided with a stepped slot defining a relatively narrow portion and a relatively wide portion inward of said narrow portion; knife holders movably supported in said slot; a knife holder guide secured to 125

each holder, said knife holder guides slidably mounted in said relatively wide portion of said slot; knives carried by said holders; and flexible connections between said rotatable shaft and said holders for periodically actuating said holders upon rotation of said shaft.

7. A fruit coring machine comprising a rotatable shaft; a bifurcated enlarged head on one end of said shaft; knife holders movably supported in said bifurcation; guide members movably connected with said rotatable shaft; each knife holder provided with an oval shaped bore adjacent the outer end thereof; a pin mounted in each bore; said pins pivotally secured at one end thereof to said holders for limited lateral movement in said bores; resilient means in said holders bearing against said pins; and anti-friction means carried by said pins for engagement with said guide members.

8. A fruit coring machine comprising a frame; a rotatable shaft supported by said frame; said shaft provided with an enlarged slotted head; a pair of jaw members vertically slidable in said frame; a channeled guide member pivotally supported by each jaw member, said channels jointly defining an oval shaped guide; a pair of knife holders slidably mounted in said slot and each provided with a roller engaged in said channel guide; coring knives carried by said holders; a pair of levers pivotally secured intermediate their ends to said frame; toggle connections between one of the ends of said levers and said rotatable shaft for intermittently operating said levers and manually adjustable means between said jaw members and the other ends of said levers for bodily shifting said jaw members with respect to said ends.

9. The construction defined in claim 8 in which said guide members are each provided with a pair of laterally spaced channel members separate from said first named channels; a pair of vertically disposed laterally spaced guide rods pivotally connected at the inner ends thereof to said frame and detachably connected at the outer ends thereof to said frame; said guide rods normally disposed in said channel members for guiding said guide members.

10. The construction defined in claim 8 in which said manually adjustable means comprises a sleeve disposed in an aperture in said jaw holder; a shoulder on the inner end of said sleeve; a nut threaded on the outer end of said sleeve; a compression spring surrounding said sleeve to normally hold said shoulder in engagement with the inner face of said jaw holder; a rod extending through said sleeve and connected to said lever; a bifurcated member detachably supported on the outer end of said sleeve into the bifurcation of which the outer end of said rod normally extends; a cam member mounted in

said bifurcation for adjustable engagement with said rod; and yieldable means in said bifurcated member for frictionally engaging said cam member.

11. In a fruit coring machine, a frame; a shaft journaled for rotation in said frame; said shaft provided with a pair of longitudinally spaced shoulders; a cam member provided with an elongated sleeve in engagement with said shaft and abutting one of said shoulders at one end thereof; a combined ratchet and registering disk mounted on said shaft outward of said sleeve and abutting the other of said shoulders and the opposite end of said sleeve; said combined ratchet and registering disk secured to said shaft by a key; a bushing in said frame through which the outer end of said shaft extends; a nut threaded on the outer end of said shaft for engagement with said frame to draw said sleeve and said ratchet and registering disk into engagement with said shoulders, coring knives connected to said shaft, and jaws actuated by said cam.

12. A fruit coring machine comprising a hollow shaft; coring knives movably supported by one end of said shaft; a coring knife adjusting cam member provided with an elongated sleeve loosely mounted on said shaft; a driving gear loosely mounted on said sleeve; a clutch disk fixed on said sleeve adjacent said gear; driving means between said gear and said clutch disk adapted to be periodically thrown into operative position; ratchet and registering means fixed to said shaft outward of said sleeve; means carried by said clutch disk for releasing said registering means for rotation; other means carried by said clutch disk for imparting rotation to said ratchet; and operating connections between said cam member and said coring knives.

13. The construction defined in claim 12 in which said ratchet and said registering means are rigidly connected; said ratchet provided with diametrically opposed teeth; said registering means provided with diametrically opposed recesses; a pawl pivotally mounted on said clutch disk and yieldably held in engagement with said ratchet; a finger pivotally mounted at one end and provided at the opposite end with a projection for engagement with one of said recesses; a projection carried by said clutch disk to engage said finger upon rotation of said disk to release said projection from said recess immediately preceding engagement of said pawl with one of said teeth; and a latch member adapted to engage said pawl to release the same from said tooth immediately preceding entrance of said projection into the other of said recesses.

14. The construction defined in claim 12 in which a cam member surrounds said clutch disk for engagement with a yieldably mounted

ed reciprocating plunger; a pit kick-out rod mounted in said hollow shaft; and flexible connections between said plunger and said kick-out rod.

15. A fruit coring machine comprising a frame; a hollow shaft rotatably mounted in said frame; coring knives movably carried by one end of said shaft; a cam provided with a sleeve loosely mounted on said shaft; cam driving means mounted on said sleeve; shaft driving means fixed on said shaft adjacent said cam driving means; movable guides for said coring knives; jaw holders pivotally connected to said guides; jaws carried by said jaw holders; toggle operating connections between said cam and said jaw holders; a hollow gauge rod slidably disposed in said hollow shaft; a tubular member threadedly engaged with the outer end of said rod; said tubular member provided with a circumferential channel; a fork engaged in said channel; a vertically disposed rod connected at one end thereof to said fork and at the opposite end thereof to a longitudinally reciprocating member; and a second rod connecting said reciprocating member to one of said toggle operating connections.

16. The construction set forth in claim 15 in which a pit kick-out rod is disposed in said hollow rod; a cam surrounding said cam driving means; a yieldably mounted plunger in engagement with said cam; and flexible connections between said plunger and said rod.

35 17. In a fruit coring machine; a rotatable shaft; adjustable coring means driven by said shaft; means independent of said shaft for adjusting the movement of said coring means; and means for setting said shaft into 40 rotation and arresting the rotation thereof positively at the end of a half revolution thereof.

45 18. In a peach pitting machine, knife holders, knives carried by said holders; means to cause said holders to approach and recede from each other; means to rotate said holders; and means to shift said holders from the circular course during their rotation, said last named means including a pair of cams 50 mounted for movement toward and from each other; and guides to determine such movement, said guides being mounted so as to be readily removable from engagement with said cam whereby said cam may be readily removed from said machine.

55 19. In a peach pitting machine comprising a pair of jaws movable toward and from each other; pitting knives disposed in matching recesses in said jaws; means to rotate said pitting knives from said recesses and to return them thereto after cutting the pit from the peach, and mechanism for operating said jaws and knives, said mechanism including levers to which said jaws are attached by a 60 connection that readily permits the shifting

of the jaws with respect to said levers and a spring to yieldingly urge said jaws toward each other, said spring being mounted independently of the connection, whereby said jaws are connected to said lever.

70 20. A peach pitting machine, comprising a pair of jaws mounted to move toward and from each other in a circumferential recess formed in the flesh of the peach, and means to actuate said jaws, said means comprising a lever for each jaw, each lever being provided to the frame of the machine between its ends and connected to a jaw adjacent one end, the opposite end of each lever being connected to a pair of links, whose points of attachment are normally in alignment when the jaws are in opposite position; one of said links being provided with an operating arm whereby the toggles formed by said links may be broken when the jaws are separated, and means to 75 operate said arms.

80 21. A fruit coring machine including a rotatable shaft; a pair of fruit coring knives carried by one end of said shaft and movable toward and from each other; removable guiding means for said coring knives; and yieldable connections between said coring knives and said guiding means.

85 In testimony whereof I affix my signature.

ARTHUR L. DUNCAN.
